UNITED STATES PATENT OFFICE.

AUGUST MARIUS KJAERSGAARD, OF COPENHAGEN, AND CARL SOEREN JULIUS WIESE,
OF ODENSE, DENMARK.

ABSORPTION APPARATUS FOR ICE AND FREEZING MACHINES.

934,545.

Specification of Letters Patent. Patented Sept. 21, 1909.

Application filed December 1, 1908. Serial No. 465,483.

To all whom it may concern:

Be it known that we, AUGUST MARIUS KJAERSGAARD, manufacturer, and CARL SOEREN JULIUS WIESE, managing director, subjects of Denmark, residing at No. 28 Frederikssundsvæj, Copenhagen, Denmark, and No. 18, Vestergade, Odense, Denmark, respectively, have invented new and useful Improvements in Absorption Apparatus for Ice and Freezing Machines, of which the following is a specification:

The present invention relates to absorption-apparatus for such ice- and freezing-machines by which through rarefaction of the air and consequent evaporation of a fluid at a low temperature is produced.

The invention consists in giving the inside of the absorption-receiver such a shape that the absorption fluid is spread over a large surface, and that the air passing through the receiver is forced to come into contact with this large surface of the fluid. By this means the absorption-fluid quickly absorbs all of the vapor contained in the air.

The invention is illustrated in the accompanying drawing in which:

Figure 1 is a vertical section through an absorption-receiver connected with a decanter the water in which is to be cooled. Fig. 2 illustrates a modified form of the upper part of the absorption-receiver. Fig. 3 is a side-elevation of the apparatus in connection with an air-pump, and Fig. 4 is a plan view of Fig. 3.

The air-pump *a* (Fig. 4) is in the described form for the apparatus driven by a crank *c* mounted on a shaft *b*. The absorption-receiver *d* is inclosed in a hood *f* which is carried partly by a swing-axle turnable on two pins *g*, partly by the one arm of an angle-lever *h* turnable on a pin *h*. The angle-lever is by a connecting-rod *m* connected with a pin on a wheel *n* carried by the axle *b*. When the axle *b* is turned, the receiver *d* will move to and fro on the pins *g* and *h*. The receiver *d* is, in order to follow these movements, connected with the suction-chamber of the air-pump *a* by means of an india-rubber-hose *p*.

The fluid containing chamber *q* which in the present instance is a decanter in which the air is to be rarefied, is placed in a basket *r* which is arranged to rock on an axle *s* and connected with receiver *d* by means of a flexible hose *t*.

The receiver *d* which generally is of glass

and contains sulfuric acid or another water absorbing fluid is cylindrical with rounded boundaries between the sides and the bottom and the cover. From the cover *v* projects downward a somewhat oblique conical plate *u* which continues the rounding between the side-wall and cover and forms an annular chamber *w* with the cover *v*, this chamber being provided with a small branch-pipe *x* upon which is fitted the hose *p*. The cover *v* has an opening to which is applied a pear-shaped retort *y* projecting into the receiver, the neck of the said retort being carried with but little play through an opening *z* in the plate *u*. The neck of the retort *y* is conical and shaped for connection with the conical end of the hose *t*. The bottom of the retort *y* is in the middle curved slightly upward so that it forms a flat cone *l* at whose bottom a row of holes *2* is arranged. The water absorbing liquid *3* in the receiver *d* reaches closely to the bottom of the retort *y*. When the receiver *d* is moved to and fro, the fluid *3* will rush along the wall and through the medium of the plate *u* it will be carried along to the retort *y* whose total surface will be constantly wetted by the liquid. The air sucked out from the chamber *q* through the hose *t* passes through the holes *2*, strikes against the surface of the fluid, ascends into the receiver *d* where it on all sides is surrounded by the water-absorbing fluid and will finally pass through the annular opening *z* where it as a thin sheet must pass through the liquid flowing down from the plate *u* so that it comes into intimate contact with the water-absorbing liquid.

Fig. 2 shows another simple form for the spreading-device. The annular chamber *w* is here formed by the bent or blown wall *v* itself. Instead of the pear-shaped retort *y* a double-walled cylinder *y'* can be used whose outer wall together with the inwardly bent part *v'* of the wall *v* forms the narrow absorption-space *z*.

The hose *t* is at both ends supplied with cones one of which, 4, is placed in the neck of the retort *y* and held there by straps *5* fastened to the lower part of the hood *f*. These straps *5* pass through holes *6* in the cover of the hood whereupon a ring *7* at the end of each strap is hooked on to a hook *8* upon the hose *t*. The other end *9* of the hose is put into the neck of the decanter *q*. The decanter *q* is together with the tank *d*

by the hose set in a swinging motion whereby the evaporation as well as the transformation of the water into ice in the decanter *q* will be accelerated. As soon as a vacuum 5 is produced in the decanter *q* by means of the air-pump, the water therein will quickly evaporate. The vapors will be sucked into the receiver *d* and absorbed by the liquid 3 whereby the low pressure in the decanter 10 will be maintained. The evaporation will then re-commence and the temperature of the water in the decanter will quickly decrease.

The whole apparatus is very compact and 15 can be easily mounted on a board 10 or the like.

Having now particularly described and ascertained the nature of this said invention and in what manner the same is to be performed, we declare that what we claim is:

1. An absorption apparatus comprising a receiver, a perforated retort mounted in the receiver and projecting through an annular chamber formed in the top of the receiver 25 and communicating with the latter through an annular opening in the bottom of the chamber, a fluid container, a flexible conduit connecting the latter with the retort, an air pump, and a flexible conduit connecting 30 the pump and annular chamber.

2. An absorption apparatus comprising a

receiver, a retort having perforations in its bottom, mounted in the receiver and projecting through an annular chamber formed in the top of the latter, said chamber communicating with the retort through an annular opening, a swinging receptacle for the receiver, a fluid container, a rockable support for the latter, a flexible conduit connecting the container and retort, an air 40 pump, and a flexible conduit connecting the pump and annular chamber.

3. An absorption apparatus comprising a cylindrical receiver having rounded ends and an annular chamber formed in its top, 45 a retort mounted in and communicating with said receiver, a swinging receptacle for the latter, an air pump, means for operating the latter, means for rocking the receptacle connected with the operating means, a fluid container, a rockable support therefor, a flexible conduit connecting the container and retort, and a flexible conduit connecting the pump and annular chamber.

In testimony whereof we have signed our 55 names to this specification in the presence of two subscribing witnesses.

AUGUST MARIUS KJAERSGAARD.
CARL SOEREN JULIUS WIESE.
